A. R. SCHMIDT

VALVE STEM CARBON REMOVER

Filed May 12, 1921

FIG. 1

FIG. 2

*Albert R. Schmidt,
Inventor
By Morsell & Keeney,
Attorneys*

UNITED STATES PATENT OFFICE.

ALBERT R. SCHMIDT, OF MILWAUKEE, WISCONSIN.

VALVE-STEM CARBON REMOVER.

Application filed May 12, 1921. Serial No. 468,917.

To all whom it may concern:

Be it known that I, ALBERT R. SCHMIDT, a citizen of the United States, and resident of Milwaukee, in the county of Milwaukee and State of Wisconsin, have invented new and useful Improvements in Valve-Stem Carbon Removers, of which the following is a description, reference being had to the accompanying drawings, which are a part of this specification.

10 This invention relates to improvements in valve stem carbon removers, more particularly adapted for internal combustion engines.

15 The ordinary internal combustion engine is provided with tappet valves for controlling the charge inlet and the exhaust outlet openings of the cylinders, and these valves have stems which are guided and extend outwardly through portions of the cylinders 20 to the reciprocating mechanism. The portions of the valve stems within the exhaust passageways are exposed to the exhaust gases, which cover the valve stems with carbon and have a very corrosive action 25 upon the stems and cause them to stick, and the valves cannot reciprocate to open or closed position, and it is necessary to take the engine apart to clean the valves. This necessitates comparatively expensive repair 30 bills, and is otherwise objectionable.

35 It is one of the objects of this invention to overcome these objectionable features and provide a means for removing carbon from the valve stems which is automatic in its action and does not require any attention.

40 A further object of the invention is to provide a valve stem carbon remover which may be easily placed within the ordinary engine without requiring any changes in the construction.

45 A further object of the invention is to provide a valve stem carbon remover having means for eliminating noise from the movable parts.

50 A further object of the invention is to provide a valve stem carbon remover which is of simple construction, is strong and durable, and is well adapted for the purpose described.

With the above and other objects in view, the invention consists of the improved valve stem carbon remover and its parts and

combinations as set forth in the claims, and all equivalents thereof.

55 In the accompanying drawing in which the same reference characters indicate the same parts in all of the views:

Fig. 1 is a vertical sectional view of the upper portion of an internal combustion engine provided with the improved carbon remover; and

Fig. 2 is a perspective view of the remover.

Referring to the drawing, the numeral 5 indicates the upper portion of an internal combustion engine which is provided with the usual exhaust opening 6 controlled by a tappet valve 7. The valve is formed with a stem 8 which extends reciprocally through the guide 9 and is held in closed position by a coiled spring 10. A rocker arm 11 actuated by a push rod 12 moves the valve to open position. The portion 8' of the valve stem between the valve 7 and the guide 9 is in the path of the exhaust gases, and carbon and burnt oil settle on the stem and interfere with the free movement of the stem in its guide and prevent the closing of said valve and consequently loss of compression and ignition of the charge with the result that the charge is wasted.

70 It has been found that if a loose member 13 preferably formed of metal is placed around the valve stem, between the valve and the guide, so it could freely slide up and down and vibrate sideways on the stem, the constant agitation of the member will prevent carbon from settling on the stem or 75 scrape off any particles that do settle, with the result that the stem is maintained in a clean condition and will not stick in the guide.

80 To deaden or eliminate the noise of the 85 vibrating member, said member is preferably split as indicated by the numeral 14.

85 It is to be understood that each exhaust valve stem of a multi-cylinder engine is to be provided with the annular members, and that the inlet valve stems may also be provided with the rings or washers, if desired.

90 While the remover has been described as a ring or washer, it is to be understood that any kind of an annular member may be 105 loosely mounted on the valve stem.

95 From the foregoing description it will be

seen that the valve stem carbon remover is of very simple construction, is strong and durable and is well adapted for the purpose described.

5. What I claim as my invention is:

1. The combination with an internal combustion engine having a valve provided with a guided stem, of a means for preventing the formation of carbon on the valve stem, consisting of a member loosely mounted on the stem between the valve portion and the stem guide and freely movable laterally and vertically thereon independently of the movement of the valve.

10. 2. The combination with an internal combustion engine having a valve opening and a valve stem guide, a valve closing said opening and having a stem guided in said guide, and a ring-like member loosely mounted on the valve stem between the valve portion and the stem guide and freely movable laterally and vertically thereon independently of the movement of the valve for removing carbon therefrom.

15. 3. The combination with an internal combustion engine having a valve opening and a valve stem guide, a reciprocal valve closing said opening and having a valve stem guide, and a split ring-like member loosely mounted on the valve stem between the valve portion and the stem guide and freely

movable laterally and vertically thereon independently of the movement of the valve for removing carbon therefrom.

4. The combination with an internal combustion overhead valve engine having an exhaust opening and a valve stem guide, a reciprocal valve controlling said exhaust opening, and a ring-like member loosely mounted on the valve stem between the valve portion and the stem guide and freely movable laterally and vertically thereon independently of the movement of the valve for removing carbon therefrom.

45. 5. The combination with an internal combustion overhead valve engine having an exhaust duct and a valve opening leading thereto, said engine also having a tubular valve stem guide extending vertically into the exhaust duct above the valve opening, 50 a reciprocal valve controlling the valve opening and having a valve stem reciprocally extending through the valve stem guide and freely movable laterally and vertically thereon independently of the movement of the valve, and a split ring-like member loosely mounted on the valve stem between the valve portion and the stem guide for removing carbon therefrom.

55. In testimony whereof, I affix my signature.

ALBERT R. SCHMIDT.
